UNITED STATES PATENT OFFICE

2,635,940

CABINET

Melinda C. Fritze, St. Louis, Mo.

Application November 18, 1950, Serial No. 196,467

1 Claim. (Cl. 312—120)

1

This invention relates to cabinets, and more particularly, to a cabinet for protecting recipe books and the like, both in storage and in use.

Briefly, the cabinet of this invention comprises a framework having sides, a bottom and an open top. A window formed of transparent material closes the front of the frame, and a front panel is movably mounted within the frame so as to be adjustably positionable toward and away from the window, thereby providing a front compartment for receiving an opened recipe book for inspection through the window, as by a person engaged in cooking. A rear panel extends across the frame behind the front panel, thereby providing a rear compartment for storing books when not in use. The frame is pivoted on a stand so that it may swing to a position for convenient viewing of the front compartment or to a position for convenient access through the open top to the other compartment.

Among the features of the invention are a simple compact cabinet construction adapted for the storage of recipe books and the like in such manner as to be readily accessible; and the provision of a cabinet adapted to support a selected book in opened position for use, while protecting the book against soiling. Other features will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claim.

In the accompanying drawings, in which one of various possible embodiments of the invention is illustrated,

Fig. 1 is a front view of the cabinet of this invention;

Fig. 2 is a side view of Fig. 1, showing alternative positions of parts in dotted lines;

Fig. 3 is a top view of Fig. 1;

Fig. 4 is an enlarged sectional view on line 4—4 of Fig. 1; and,

Fig. 5 is a perspective view of the drawer.

Similar reference characters indicate corresponding parts throughout the several views of the drawings.

Referring now to the drawings, the cabinet of this invention is shown to comprise a frame 1 having sides or ends 3 and a bottom 5. The sides and bottom of the frame are formed from flat panels of equal width secured together at their ends in the shape of a U so as to leave

2

open the top 7 of the frame. Narrow strips 13 are secured across the top corners of the side panels 3 so as to provide bracing at the top. The front of the frame is closed by a sheet 15 of transparent material, such as glass, which is set within a channel 17 formed around the front of the frame. Thus, there is provided a box-like frame having an open top 7, a front window 15 and an open rear 18.

- 10 10. The box-like frame is divided into a front compartment 19 for receiving an open book 21 and a rear compartment 23 for the storage of other books 25 and the like. There is provided within the frame a front panel 27 which cooperates with the window 15 to form the front compartment 19. A rear panel 29 cooperates with the front panel 27 to form the rear storage compartment 23. Side or end members 31 and a bottom 33 are secured to the front and rear panels 27 and 29 so that together they form a drawer-like structure 35, the top of which is open. This drawer is slidably received within the frame so that it may be moved toward and away from the window 15, its width being less than that 15 of the box-like frame. The drawer is adjustably maintained in position by means of a bolt 37 affixed to the bottom 33 of the drawer and extending through a slot 39 formed in the bottom 5 of the frame. A metal guide plate 41 may 20 be affixed to the underside of the frame and a nut 43 is threaded over the bolt 37 for cooperation with the guide plate. The slot 39 opens to the rear so as to permit removal of the drawer 35, if desired.
- 20 35. The provision of the movable front panel 27 behind the window 15 permits the size of the front compartment 19 to be varied in accordance with the thickness of the opened book to be received therein. An opened book may be 30 pressed flat against the window by the panel 27 so as to be readily readable even in the otherwise curved portions at the binding. Since the items stored in the rear compartment rest upon the sliding bottom 33 of the drawer, they will 40 not interfere with the movement of the drawer 35 and front panel 27.

The frame 1 is pivoted at its sides 3 upon a stand generally designated 45. The stand is formed with a base 47 from which extend uprights 49 on opposite sides of the frame. Bolts 51, fixed in each of the sides 3 of the frame, pass through the respective uprights 49 of the stand. Nuts 53 are threaded over the bolts 51, the arrangement being such that the frame may be 50 55 swung on the stand, then held in a relatively

fixed position as by tightening the nuts 53. A flat tray-like drawer 55 is incorporated in the base 47 of the stand to receive loose recipe slips and the like not conveniently stored in the rear compartment 23.

It is contemplated that the cabinet will be placed on the top of a kitchen table or the like for use, and that recipe books will be stored in the rear compartment 23. When it is desired to make use of one of the stored books 25, the frame 1 is swung forward or away from the vertical position to a position A (Fig. 2), wherein the open top faces the user (the window facing generally down) so that books stored in the rear compartment are readily accessible. It will be understood that the books may be stored with their bindings facing toward the open top for view, instead of on their ends as shown in Fig. 3. A book may be readily removed from the rear compartment, opened and slipped into the front compartment 19. The frame is then swept back generally to a vertical position B or further back as at C if desired, and the drawer 35 is adjusted forward to press the open book against the window 45. The user may then proceed with the actual preparation of a recipe, making reference from time to time to the opened book 21 without danger of soiling it.

From the above, it will be apparent that there is provided a cabinet particularly adapted for recipe books or other items which are likely to be damaged when in use. The cabinet is formed with a tiltable guide 1 having a front window 45 and a hollow slide member 35 arranged to clamp an opened book against the window and store other books.

In view of the above, it will be seen that the

several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

10 A cabinet for recipe books and the like, comprising a U-shaped frame having sides, a bottom and an open top, a sheet of transparent material closing the front of the frame and forming a window, a drawer slidably received within the frame and having front and rear panels extending parallel to said window generally completely across the frame, means for adjustably fixing the position of said drawer with respect to the window, the drawer being open at the top for access thereto through the top of the frame, and a stand pivotally supporting the frame at its sides for swinging movement with respect to the stand from a position for convenient access to the drawer to a position for convenient viewing through the window.

MELINDA C. FRITZE.
